CLAIM

The ornamental design for a lightning discharge strip, as shown and described.

DESCRIPTION

FIG. 1 is a front perspective view of a lightning discharge strip showing the new design of the present invention;

FIG. 2 is a top plan view thereof;

FIG. 3 is a front elevational view thereof, which view is identical to the rear elevational view;

FIG. 4 is a left end view thereof, which view is identical to a right end view thereof; and,

FIG. 5 is a bottom plan view thereof.

The broken line showing throughout the drawing figures is included for the purpose of illustrating environmental structure only and forms no part of the claimed design.
